PLASTIC CARRYING TRAY

Michael Rodolakis, Worcester, Mass., assignor to Dapol
Plastics Inc., Worcester, Mass.

Filed Aug. 27, 1969, Ser. No. 18,906

Term of patent 14 years

Int. Cl. D3—99

U.S. Cl. D87—1

FIG. 1

↑₂

FIG. 2

↑₃

FIG. 3

FIG. 1 is a top plan view of a plastic carrying tray showing my new design;

FIG. 2 is a view in side elevation thereof looking in the direction of arrow 2 in FIG. 1, and

FIG. 3 is an end view in elevation thereof looking in the direction of arrow 3 in FIG. 2.

I claim:

The ornamental design for a plastic carrying tray, as shown.
